UNITED STATES PATENT OFFICE.

THOMAS A. CONKLIN, OF NEW BRITAIN, CONNECTICUT.

IMPROVEMENT IN ICE-PICKS AND MEAT-MAULS COMBINED.

Specification forming part of Letters Patent No. 128,020, dated June 18, 1872.

To all whom it may concern:

Be it known that I, THOMAS A. CONKLIN, of New Britain, in the county of Hartford and State of Connecticut, have invented a new and Improved Ice-Pick and Meat-Maul, of which the following is a specification:

My invention consists of a hammer-shaped implement having a cluster of conical points upon its face, and a single sharp point directly opposite said face, and a cast handle, said parts all being cast in one and the same piece of metal. My invention also consists in the peculiar construction of the handle, as hereafter described.

In the accompanying drawing, Figure 1 is a side elevation of an implement which embodies my invention, and Fig. 2 is a side elevation of the handle thereof previous to being finished.

The general form of the implement is hammer-shaped, as shown in Fig. 1. The face of the head A is provided with a cluster of conical points, a, and is designed for use as a meat-maul. The conical points are believed to be better than square or rectangular ones, as they displace the fibers of the meat and make it tender without badly mangling and spoiling its shape. The point B at the opposite end of the

head A is designed for an ice-pick. The head A, as described, is cast in one and the same piece with the handle C. The handle C near the large end is cast in skeleton form, with a recess, b, in each side, as shown in one side in Fig. 2. The recesses b b are filled with hard wood d, Fig. 1, and firmly pressed therein, when rivets e e or screws are passed through the wood d and the open parts of the handle C, and their ends upset, when the wood is held firmly within the recesses, and may be smoothed off or finished as desired.

This construction of the handle is very cheap, light to handle, of very neat finish, furnishes a good gripe for the hand, and by being cast in the same piece with the head is not liable to be accidentally detached therefrom.

I claim as my invention—

The improved hammer-shaped implement herein shown, consisting of the head A, point B, cluster of conical points a, and handle C, all relatively arranged and cast in one and the same piece of metal, substantially as and for the purpose described.

THOMAS A. CONKLIN.
